UNITED STATES PATENT OFFICE,

E. BRUCE PRESTON, OF CHICAGO, ILLINOIS.

DESIGN FOR A RUBBER BOOT OR SHOE.

SPECIFICATION forming part of Design No. 16,208, dated August 18, 1885.

Application filed June 15, 1885. Term of patent 7 years.

To all whom it may concern:

Be it known that I, E. BRUCE PRESTON, a citizen of the United States, residing in Chicago, in the county of Cook and State of Illinois, have 5 invented a new and original Design for Rubber Boots and Shoes, of which the following is a specification.

This design relates to rubber boots and shoes, and is illustrated in the accompanying drawing, where a boot embodying the design is shown in perspective.

The leading feature of my design consists of a raised front vertical rib and encircling bands upon the leg of the boot, and a central rib and 15 diagonal side ribs upon the upper, the diagonal ribs being joined at intervals by bands, substantially as hereinafter described.

The surface of the boot is provided with a wide central vertical raised rib, *a*, in front. 20 It is also provided with bands *b*, running around the leg in an inclined direction—that is, the ends meet at the rib *a* in front, and from thence incline upward toward the back. The bands are similar to rib *a* in character, except that 25 they are narrower, so that at their junction both are of the same height and merge together in such manner as to appear integral. The upper of the boot or shoe has a central raised rib, *c*, and diagonal side ribs, *d*, extending 30 from *c* backward toward the sole. The side ribs are joined at intervals by connecting bands *e*, thereby dividing the surface into parallelograms. These ribs *c*, *d*, and *e* resem-

ble the ribs of the leg, and merge at their junction so as to appear integral in the same 35 manner. The bands *e* break joints with one another—that is to say, they alternate in adjacent rows, as clearly shown in the drawing.

While the main feature of my design relates to the ornamentation of the entire boot, yet 40 my design is also applicable to shoes, as the design shown for the upper is obviously adapted to use with shoes. It is also apparent that the ornamentation upon the leg may be employed where the upper is differently ornamented. Hence I desire to lay claim to these 45 features as sub-designs.

I claim—

1. The design for a rubber boot herein shown, consisting of the vertical rib *a* and inclined bands *b*, and the upper whereof is provided with the ribs *c* *d* and connecting bands *e*, all substantially as described and shown. 50

2. In a design for rubber boots, the ornamentation for the leg, consisting of the central vertical rib, *a*, and encircling bands *b*, substantially as described and shown. 55

3. In a design for rubber boots and shoes, the ornamentation for the upper, consisting of the ribs *c* and *d* and connecting bands *e*, substantially as described and shown. 60

E. BRUCE PRESTON.
